UNITED STATES PATENT OFFICE.

KEYES A. HATHAWAY, OF ROCKFORD, ILLINOIS.

DESIGN FOR A HANDLE FOR KNIVES, &c.

SPECIFICATION forming part of Design No. 20,647, dated March 31, 1891.

Application filed January 29, 1891. Serial No. 379,583. Term of patent 7 years.

To all whom it may concern:

Be it known that I, KEYES A. HATHAWAY, a citizen of the United States, residing at Rockford, Winnebago county, and State of Illinois, 5 have invented a new Design for the Handles of Knives, Forks, and Spoons; and I do hereby declare the following, when taken in connection with the accompanying illustration, to be a full, clear, and exact description of the 10 same.

The illustration represented shows my design as applied to the handle of a knife.

That portion of the handle bearing my design is formed with diverging sides and a 15 curved outer end. A border is traced on the face of the handle near to and parallel with the outer edge, forming a marginal rib bounding the design.

Between the marginal sides at a point near 20 the middle of the design a small shield ex-

tends diagonally from border to border across the face of the design, separating daisy-blossoms at the outer end of the handle from pansy-blossoms at the inner end, pansy and daisy leaves interposed between the blossoms filling 25 in the ground-work of the design.

The scroll-shield is irregular in form and consists of a series of scrolls each diverging from the main portion.

I claim as my invention—

A design herein described and shown for the handles of knives, forks, and spoons, consisting of an ornamentation representing pansy and daisy blossoms on a ground-work of leaves and a diagonal shield separating 35 the pansies from the daisies.

KEYES A. HATHAWAY.
